UNITED STATES PATENT OFFICE.

LOGAN L. MALLARD, OF ATLANTA, GEORGIA, ASSIGNOR OF ONE-HALF TO
WM. A. SIMS, OF ATLANTA, GEORGIA.

CUFF-HOLDER.

No. 858,300.

Specification of Letters Patent.

Patented June 25, 1907.

Application filed May 24, 1906. Serial No. 318,578.

To all whom it may concern:

Be it known that I, LOGAN L. MALLARD, a citizen of the United States, residing at Atlanta, in the county of Fulton and State of Georgia, have invented certain new and useful Improvements in Cuff-Holders, of which the following is a specification.

The object of my invention is to provide an improved cuff holder the construction of which will afford economies in the manufacture of the device and will produce an article of this character which will be of comparatively few and simple parts that are durable in construction and efficient in operation to hold a cuff securely at the proper length with respect to the coat sleeve, and the invention comprises particularly, in addition to the details of construction relating to the manufacture of the device an improved cuff member which will securely hold the cuff in place without injury to the fabric, and which may be readily applied to and detached from the cuff, and a spring clip sleeve member designed to be attached to the shirt sleeve in a secure manner without injuring the fabric thereof as articles of this character often do.

For a full description of the invention and the merits thereof and also to acquire a knowledge of the details of construction, reference is to be had to the following description and accompanying drawings, in which:

Figure 1 is a perspective view illustrating the application of my improved cuff holder; Fig. 2 is a detail perspective view of the wings of the cuff member; Fig. 3 is a detail perspective view of the supporting plate for said wings; Fig. 4 is a longitudinal sectional view of said plate; Fig. 5 illustrates the wing supporting plate in blank form and in juxtaposition to the connecting member adapted to connect said plate with the sleeve engaging member of the device; Fig. 6 is a detail longitudinal sectional view of a spring plate forming part of the cuff member; Fig. 7 is a detail plan view of the same; Fig. 8 is a detail perspective view of a modification of said spring plate; Fig. 9 is a side elevation of the cuff member; Fig. 10 is a detail view illustrating a modified form of wing; Fig. 11 is a detail view of two of the minor parts; Fig. 12 is a top plan view of a modified form of cuff holder; Fig. 13 is a view of parts of said modified form; Fig. 14 is a transverse sectional view on the line 14—14 of Fig. 12; and, Fig.

15 is a detail perspective view of the sleeve 5 engaging member.

Corresponding and like parts are referred to in the following description and indicated in all the views of the drawings by the same reference characters.

Referring to the drawings, and now particularly to Figs. 1, 3, 4, 5 and 9, the numeral 1 designates the cuff member of my improved cuff holder, the same comprising a plate that may be stamped out of blank form illustrated in Fig. 5 and perforated as required in one and the same operation and subsequently die curled or bent to the proper contour. When so bent, it is formed with an overhanging edge 1^a from the opposite sides of which the apertured ears 4 project, and the side edges of the plate are so formed at one end, as to produce two meeting flanges 5 adapted to encircle the tapered head 6 of the rod-like shaft 7 of a connecting member 3. In connection with the said plate, just described, the cuff member embodies a pair of wings 8 which may be suitably stamped out of sheet metal and each wing is provided with apertured ears 9 designed to receive a pintle 10 inserted therethrough and through the ears 4. Each wing 8 is provided at its hinged edge with lugs 11 designed to contact with a spring plate 12, which may be substantially of the same marginal outline as the plate to which the wings are hinged, said spring plate being preferably held by means of the curled over edges 1^a. As illustrated in Fig. 8, this spring plate may be of the form designated 12^a. Each wing 8 is provided at its free end 9^c with a rough surface; the said surface may be a serrated portion as shown in Fig. 2 and the purpose of this roughened surface as is manifest, is to produce a frictional or biting surface to engage the fabric of the cuff.

As shown in Fig. 10, it is within the purview of my invention to construct each wing designated 8^a with curled or knuckle-like ears 9^a and with short spurs 13 to bite into the cuff.

The sleeve engaging member 2 of the cuff holder, as illustrated best in Figs. 1 and 15, is composed of a spring clip comprising two members 14, preferably of sheet metal provided at opposite sides with apertured ears 15 to receive the pintle end 16 of the shank 7 of the connecting member 3. This said pintle end 16 of the said shank may be pro-

vided with a shoulder 17 against which one pair of these ears will abut, while the extreme end of said pintle end may be formed into a rivet to retain the two members 14 in proper pivoted position on the connecting member 3. Each of the clip members 14 is further provided at one end with spaced apart fingers 18 preferably curved in a longitudinal direction and corrugated or curved transversely as illustrated in the drawings, the corrugations 19 preferably extending beyond the fingers on to the body portion of the said members 14. A spring 20 is provided to move the pivoted members 14 so that their fingers 18 will grip the sleeve and the said spring may be a helical spring coiled around the pintle on which the members 14 are pivoted. Preferably each clip member 14 is provided at its rear end and on its outer surface with a rough or serrated portion 21 providing a convenient finger hold. Preferably also the curved or bowed fingers 18 of the clip members 14 alternate with each other or are, in other words, arranged in a staggered relation so that they will securely clamp the fabric inserted between them in a corrugated manner which will securely grip the fabric without injuring the latter.

As illustrated in Figs. 12 and 13, the wings 30 supporting the plate 1^a of the cuff member may be extended at one end as at 1^b, the side edges of the said extension being curled as at 1^c to strengthen the extension, and the extreme end of the said extension being provided with flanges 5^a encircling the section 6^a of the comparatively short member 3^a. In this modification, the sleeve engaging device is designated 2^a and the clip member thereof of 14^a.
40 In the practical application of my improved cuff holder, the wings 8 of the cuff member 1 are both swung perpendicular to the plate which carries them, back to back, as illustrated in Fig. 9 of the drawing, being retained in such position by the spring action of the spring plate 12 or the plate 12^a, as the case may be. The said two wings are inserted through the button hole of either or both tabs of the cuff and are then swung 50 downwardly away from each other, which action will securely grip the cuff, both by the

direct contact between the free ends of the wings and the fabric of the cuff and by reason of the fact that the said wings extend outwardly on opposite sides of the button hole. 55 The said wings will be retained in this operative position by the spring engagement of the lugs 11 with the spring plate above mentioned.

From the foregoing description it is evident that the wings need not pierce the fabric of the cuff to insure the proper retention of the latter, and therefore they will not injure the fabric as devices of this character often do. 60

It is obvious that the cuff may be secured on the wearer's wrist at the proper position with reference to the coat sleeve by the spring clip constituted by the members 14 with their fingers 18 which are spaced apart 70 as above described and alternate with each other so as to securely hold the fabric of the shirt sleeve between them in a corrugated outline, thereby securely holding the fabric as against the lengthwise pull and strain to 75 which the cuffs will be subjected and without injuriously affecting the fabric of the sleeve.

Having thus described the invention, what is claimed as new is: 80

A cuff holder, comprising a plate having overhanging marginal edges and formed at opposite points in said edges with apertured ears, and also formed at one end with curled over flanges, two transversely extending 85 wings pivoted to said ears, said wings being provided at their pivoted edges with lugs, a spring plate mounted within the first named plate between the bottom of the latter and the said wings and retained in said first 90 named plate by the said overhanging edges, a sleeve engaging member, and a rod-like connecting member secured at one end to the sleeve engaging member and provided at its other end with a tapered head received 95 in and held by the said curled over flanges.

In testimony whereof I affix my signature in presence of two witnesses.

LOGAN L. MALLARD. [L. S.]
